WILLIAM F. HUDSON, OF PHILADELPHIA, PENNSYLVANIA.

COOLING SYSTEM FOR INTERNAL-COMBUSTION ENGINES.

1,285,711.

Specification of Letters Patent. Patented Nov. 26, 1918.

Application filed February 1, 1917. Serial No. 146,014.

To all whom it may concern:

Be it known that I, WILLIAM F. HUDSON, a citizen of the United States, residing at Philadelphia, in the county of Philadelphia 5 and State of Pennsylvania, have invented a certain new and useful Improved Cooling System for Internal-Combustion Engines, of which the following is a specification.

The principal object of the present invention is to provide a cooling system for internal combustion engines in which the cooling liquid is so conserved that a desired level is maintained substantially constant through long periods of time whereby immediate circulation of the cooling liquid may be had simultaneously with the starting of an engine. A further object of the present invention is to utilize for this purpose with as few 15 charges as possible, such parts of systems of cooling by radiation as are used at present in connection with internal combustion engines, so that the installation cost of the present system may be reduced to a minimum.

Other and further objects of the present invention reside in the providing of general details of construction and arrangement of parts as will hereinafter appear.

With these and other objects in view, the invention consists of the improvements hereinafter described and finally claimed.

The nature, characteristic features and scope of the invention will be more fully understood from the following description 35 taken in connection with the accompanying drawings forming part hereof, and in which:

Figure 1 is a view in elevation partly sectioned illustrating an internal combustion engine and radiator showing a form of cooling system of the invention in application thereto;

Fig. 2 is a similar view illustrating a slightly modified form of construction;

Fig. 3 is a similar view of another form of construction; and

Fig. 4 is a similar view of still another form of construction.

For the purpose of illustrating my invention, I have shown in the accompanying drawings one form thereof which is at present preferred by me, since the same has been found in practice to give satisfactory and reliable results, although it is to be understood that the various instrumentalities of

which my invention consists can be variously arranged and organized and that my invention is not limited to the precise arrangement and organization of the instrumentalities as herein shown and described. 60

In the drawings, the internal combustion engine, which may be of any desired type, is designated 10 and its complemental jacket through which the cooling liquid passes is designated 11. Communication is established between the jacket 11 and the radiator 12 by means of usual cooling liquid circulating connections 13 and 14. With the exception of the radiator 12, none of the above indicated parts need be altered by the 70 adoption of the system of cooling by radiation about to be described.

While the present form of cooling system is applicable to various kinds of internal combustion engine, it is particularly adaptable for use upon automobiles and for illustrative purposes the following description will be restricted thereto. The cooling apparatus of most cars is of the thermo-siphon type wherein hot water seeks a higher level 75 than cold water. When the water in such systems reaches a certain heat, circulation takes place and water in the radiator flows from the lower portion of radiator to and through engine water jacket from whence it 80 passes to the radiator top. With resultant expansion in the radiator water escapes therefrom through an overflow pipe. This constitutes a waste and frequent radiator filling is necessary. In the practice of the 85 present invention, I remove such overflow pipe from the radiator.

A description will now be given of the apparatus disclosed in Fig. 1. Adjacent the rear upper portion of a radiator as applied 90 to modern cars is an offset or enlarged portion 15. The rear wall of this offset I temporarily remove. I then insert through the opening formed in the offset a box-like structure 16 forming an auxiliary cooling liquid 160 retaining chamber provided with an inlet and at least one outlet port as 17 and 18 respectively. The inlet port 17 is arranged to extend upward into the neck 19 of the radiator, through which neck the cooling liquid is 105 poured. The port 18 is provided with an outwardly opening valve 20 which may be of any desired construction suitable for the purpose. The rear wall of the auxiliary cooling liquid retaining chamber may be 110

provided with a drip cock 21. Straps 22 or the like may be employed for securing the said chamber with respect to the offset 15. I now replace the rear wall of the radiator 5 so that drip cock 21 projects therethrough as shown. Such arrangement of parts is very simple in construction, very inexpensive to make and may be readily applied to existing motor-car radiators with change 10 other than above noted. In some instances, instead of placing a box-like receptacle within the radiator, I build up said offset to form an auxiliary chamber 23. In such case, I add to the offset a front wall 24, see Fig. 2, 15 to complete the chamber. An inlet port 17 and at least one outlet port 18 and a drip cock 21 are provided as above described.

In Fig. 3 in addition to adding to the offset the front wall 24, I reconstruct the rear 20 of the offset to provide a much enlarged auxiliary chamber.

In some instances offset 15 may not be present upon a radiator in which case the auxiliary chamber is manufactured complete 25 as shown in Fig. 4. In said figure, the auxiliary chamber is designated 26 and the connections between the same and the radiator are designated 14' and 15'. It is to be understood that the auxiliary chamber in all 30 instances is to be located at a point above the return connections 14 of the radiator. In all of the above instances, the operations are the same and a description thereof will now be given.

35 The cooling liquid, usually water, is poured through the neck 19 of the radiator to initially charge the jacket of the engine and radiator. Should any cooling liquid find its way into the auxiliary chamber in 40 filling the radiator, the same may be drained therefrom through drip cock 21. Instead of drip cock 21, a closure as a cap 31 or the like may be temporarily fitted over the chamber inlet connection to prevent access 45 of liquid to the chamber which closure is removed after the filling of the system with cooling liquid. With the starting of the engine the cooling liquid in the engine jacket becomes heated and a circulation 50 thereof takes place between said jacket and radiator in a well understood manner. When the cooling liquid becomes heated, sometimes to the boiling point, a portion of the cooling liquid in its circulation is forced 55 up into the auxiliary chamber, pressure within the radiator being sufficient to maintain closed the valve or valves 20, thus retaining for use later on an auxiliary supply of cooling liquid. During the circulation 60 of the cooling liquid, it may be desirable to permit escape of any vapor present in the radiator. This may be accomplished by aperturing filler cap 29 (Fig. 1) or placing an outwardly opening valve 30 in 65 said filler cap, see Fig. 2. With the stop-

ping of the engine the temperature of the cooling liquid is reduced and pressure within the radiator is decreased with the result that the weight of the retained or stored cooling liquid in the auxiliary chamber 70 moves at least one valve 20 from its seat and permits said liquid to pass to the radiator. Thus the circulation system is again fully charged so that a complete cycle of cooling liquid is available upon restarting of the engine. In this respect it may be stated that the level of the cooling liquid in the radiator should at least be slightly above the outlet opening of connection 14. Should several valves 20 be employed, then with the 75 engine stopped, if the level of the cooling liquid be above the lowermost valve, obviously only the upper valve will open and the residue of the cooling liquid will be 80 conserved for use when a deficiency of the cooling liquid in the circulating system permits 85 of the escape of same.

By the above described system of cooling, it will be observed that the cooling liquid is so conserved that a desired level is maintained substantially constant through long periods of time whereby immediate circulation thereof may be had simultaneously with engine starting. Further it will be noted that this system may be installed at 90 small cost in that but minor changes are required in its adoption.

Among the advantages of the above described system, mention may be made of the following: The radiator water level is 100 maintained substantially the same for long periods of time thus overcoming the necessity of constant radiator filling; a saving of lubricating oil is effected because the same is not caused to "burn;" the formation of 105 carbon in the cylinders is greatly reduced; overheating of the engine is reduced to a minimum and as constant filling of the radiator is eliminated, the amount of sediment and incrusting solids present in the cooling 110 system is of a negligible character. Other advantages are apparent without further description thereof.

It will now be apparent that I have devised a novel and useful construction which 115 embodies the features of advantage enumerated as desirable in the statement of the invention and the above description and while I have in the present instance shown and described the preferred embodiment thereof 120 which has been found in practice to give satisfactory and reliable results, it is to be understood that the same is susceptible of modification in various particulars without departing from the spirit or scope of 125 the invention or sacrificing any of its advantages.

What I claim is:—

1. Apparatus of the character stated embracing a main cooling liquid circulation 130

liquid during a circulation period and laterally disposed valves for the direct return of said discharge into the main circulation system during a cooling period said valves being maintained closed during a circulation period by pressure within the circulation system.

In testimony whereof, I have hereunto signed my name.

WILLIAM F. HUDSON.
